6 Claims. (Cl. 315—27)

1

This invention relates to combination deflecting and high-voltage supply circuits for use with cathode-ray tubes.

It has been customary for some time, in television and other cathode-ray tube systems, to provide circuits in which a portion of the energy from a source which supplies the signal for deflecting the electron beam of a cathode-ray tube is rectified to provide a high D.-C. potential suitable for supplying the second anode of the cathode-ray tube. In such arrangements according to the prior art, the fraction of the total energy supplied by the deflecting signal source, which was required by the high-potential rectifying circuit, was invariably a relatively small fraction (e. g. 10%). This was largely due to the fact that the deflecting yokes commonly used in such circuits were of relatively low efficiency.

In such circuits it was customary to employ a conventional closed-core transformer for transferring energy from the deflecting signal source to both the deflecting yoke and the high-voltage rectifying circuit. Such a transformer functioned initially to transfer substantially all of the energy from the deflecting signal source to the deflecting yoke. During the return of the cathode-ray beam from the end of one line to the beginning of the next, a relatively small portion of this energy, which was stored in the field surrounding the deflecting yoke, was returned through the transformer to the high-voltage rectifying circuit.

Recently there have been developed deflecting yokes of much higher efficiency, such, for example, as the one described and claimed in my co-pending application Serial No. 164,465, filed May 26, 1950, in which the windings of the yoke are disposed at all points in close proximity to the path of the electron beam so as to exert the maximum force tending to deflect the beam at all points along its path, whereby the maximum possible deflection of the beam is effected in response to a minimum of deflecting energy.

When such a high efficiency yoke is employed in a combination deflecting and high-voltage supply circuit of the sort above referred to, the fraction of the total energy supplied by the deflecting signal source which goes to the high-voltage rectifying circuit is substantially increased (e. g. to as much as 30%) by reason of the reduction in the energy requirements of the deflecting yoke. It was found in practice however, that the advantages of increased efficiency of such yokes could not be realized in a combination deflecting and high-voltage circuit con-

structed in accordance with the prior art. Further it appeared that such an arrangement tended to provide too high a deflecting current in the yoke, while at the same time developing an insufficiently high potential for second anode supply purposes. Upon investigation of this situation it appeared that the difficulty lay in the conventional form of transformer, which, while it operated efficiently to transfer energy from the deflecting signal source to the deflecting yoke, failed to permit the supply of a sufficient fraction of the deflecting energy to the high-voltage rectifying circuit. Thus if this transformer were designed to supply the right amount of power to the deflecting yoke, then an insufficient amount of power would be supplied to the high-voltage rectifying circuit, while, on the other hand, if it were designed to supply sufficient power to the high-voltage rectifying circuit, then an unnecessarily large amount of energy would be supplied to the deflecting yoke. Further it was noted that, since all of the energy from the deflecting signal source was initially supplied to the deflecting yoke and a portion of it later returned through the transformer to the high-voltage rectifying circuit, a substantial loss (e. g. as much as 20%) resulted from this unnecessary transfer of energy from the deflecting signal source to the deflecting yoke and then from the deflecting yoke back to the high-voltage rectifying circuit.

Accordingly it is the primary object of the invention to overcome the aforementioned difficulties and to provide a combined deflecting and high-voltage supply system for cathode-ray tubes, in which both a cathode-ray beam deflecting yoke and a high-voltage second anode supply circuit, whose energy requirements constitute a relatively large fraction of the total energy supplied to both said yoke and said high-voltage circuit, are energized from a common source of deflecting signal, and in which energy is supplied from said common source to said deflecting yoke and said high-voltage supply circuit in proportion to their respective requirements and with maximum efficiency.

I have discovered that this objective can be achieved by substituting, for the conventional closed-core type of transformer customarily employed in such circuits of the prior art, an open-core transformer having an air gap sufficiently large to cause a portion of the total energy supplied by the deflecting signal source to be stored in the field surrounding the transformer, said portion being substantially equal to the portion of the total supplied energy which is required by

high-potential rectifying circuit. When such arrangement is used, there is supplied from deflecting signal source to the deflecting yoke the open-core transformer only an amount energy sufficient to satisfy the requirements the deflecting yoke. The remainder of the energy supplied by the deflecting signal source

be momentarily stored in the field surrounding the transformer and will subsequently transferred to the high-voltage rectifying circuit. In contradistinction to the mode of operation of the prior art arrangement, the portion energy supplied from the deflecting signal source to the high-voltage rectifying circuit is supplied directly from the source to the rectifying circuit without an intermediate transfer to deflecting yoke and back again. Hence the advantages inherent in the prior art arrangement are eliminated and maximum efficiency is insured.

Another feature of the arrangement in accordance with the present invention lies in the fact that the open-core transformer employed herein not only provides for the proper distribution of energy between the deflecting yoke and the high-voltage rectifying circuit to cause it to operate properly and to insure the desired overall high efficiency, but is also substantially cheaper and more readily manufactured than the conventional closed-core type employed prior art arrangements.

Other objects and advantages will be apparent from the following description of a preferred form of the invention and from the drawings, which:

Figures 1 and 2 are graphs of anode potential versus deflection energy, showing the manner in which these two factors vary for different types of cathode-ray tubes and for different deflection angles;

Figures 3 and 4 are perspective views of a preferred type of coupling transformer for use in vision deflection and H.-V. circuits designed in accordance with the present invention; and Figure 5 is a schematic diagram of one form of cathode-ray beam deflection circuit designed in accordance with the present invention and employing the transformer of Figs. 3 and 4. In order to comprehend fully the advantages of a deflection and high-voltage circuit of the nature set forth in the present disclosure, it is helpful to consider the manner in which the power developed in a television deflection circuit utilized by different types of cathode-ray tubes, will be sufficient for the purpose of the present illustration to consider four cathode-ray tubes, one of which is a standard, or conventional, tube having a 55° deflection angle, the second of which is a similar tube having a 70° deflection angle, the third of which is a 55° narrow-neck tube designed in accordance with the principles set forth in applicant's copending case above-mentioned, and the last of which is another narrow-neck tube with a 70° deflection angle.

Considering first the 55° standard tube, there shown in Figure 1 a curve of the energy which may be supplied to this tube for deflection, versus the high voltage, or anode potential, developed at any particular deflection energy value. It will be observed that the relationship takes the form of a straight line the lower portion of which within the anode potential region of approximately 8 to 10 kv.) corresponds to a domain where a standard 10" tube of this type might be operated. The above portion is followed, for higher anode voltages, by a similar one charac-

teristic of a 12" tube, then one of a 16" tube, and so on. The linearity of the curve is primarily due to the fact that any increase in deflection current (for an equal deflection angle) is proportional to the square root of the anode potential, and hence the deflection energy (which may be expressed as $\frac{1}{2} Li^2$) is directly proportional to the high voltage. In practice, various circuit losses will cause the curve to depart slightly from a perfectly linear condition.

The other curves of Figure 1 similarly indicate the anode potential versus deflection energy relationship for the other tube types mentioned above. It will be noted in this connection that, the more efficient the tube type, the steeper the slope of the line which represents it. Furthermore, while the narrow-neck 55° and 70° tubes may be deflected by a B+ supply of approximately 125 volts, the standard 55° normally requires 250 volts, and the standard 70° in the neighborhood of 330 volts.

It may readily be seen from Figure 1 that with a power input of, say, 19 watts, the standard 70° tube may be supplied with about 1 1/4 millijoules of deflection energy, and hence the maximum anode potential which can be developed is in the neighborhood of 6 kilovolts. With the narrow-neck 70° deflection angle tube, however, almost as much deflection energy is obtained from the same input, while the high voltage is increased to nearly 12 kv. when using a transformer of the type to be later described.

Figure 2 is a graph showing the number of driver tubes, and the value of B+ power supply, required for cathode-ray tubes of the types now being considered. For example, with a single 6BQ6 driver tube, and a B+ supply of 130 volts, approximately one millijoule of deflection energy is produced for a standard 70° cathode-ray tube together with approximately 4 kv. of anode potential. With a narrow-neck 70° tube, and using the transformer of the present application, nearly as much deflection energy is developed, while at the same time the high voltage output is raised to approximately 8 kv., or nearly double the amount. Other relationships are apparent from an inspection of the graph. However, a portion of the data which is available therein may be summarized in the following table:

Tube Type	Screen Diameter	H. V. (kv.)	Number of Rectifiers	B+	Driver Stage
55°				Volts	
Narrow-neck 55°	12	10	Single	130	1-6BQ6
Narrow-neck 70°	16	14.5	do	130	2-6BQ6's
55° Standard 12	12	9	do	250	1-6CD6
55° Standard 16	16	14.5	Double	250	2-6BQ6's
70° Standard 16	16	14.5	do	330	1-6CD6

It will be noticed that the graph of Figure 2 may be roughly divided into three zones. The first is a region utilizing the transformer described in the present application, the second is a section lying closer to the $\frac{1}{2} Li^2$ axis where a transformer with a closed core is normally required, and the third is an intermediate region where not only a closed core transformer but also a voltage doubler would probably be necessary and which includes a large majority of the standard cathode-ray tubes now known in the art. It is of course apparent that each location lying progressively further from the origin will require progressively larger power output tubes for satisfactory operation.

Referring now to Figures 3 and 4 of the drawings, there is shown a preferred form of coupling, or output, transformer designed for use in a circuit according to the present invention. This transformer, generally indicated by the reference numeral 10, includes a core member 12 composed of some suitable finely-divided ferromagnetic material, such as powdered iron, in combination with a binder. The core member 12 (which may also be called a "slug") is generally cylindrical form, and is enclosed within an insulating tube 14 which serves as a support upon which a plurality of coils are wound.

As hereinbefore pointed out, the configuration and dimensions of this core are chosen so as to provide an air gap in the magnetic flux path linking the windings of the transformer which is sufficiently large to cause a portion of the total energy supplied by the deflecting signal source to be stored in the field surrounding the transformer, said portion being substantially equal to the portion of the total supplied energy which is required by the high-potential rectifying circuit. Under these conditions the impedance of the transformer looking into the terminals to which the yoke is connected is small compared to the yoke impedance. In the circuit for which the present transformer was designed, the requirement of the deflecting yoke was 9 watts, while that of the high-voltage supply circuit was 3 watts. The procedures involved in designing a core to satisfy this requirement are well understood by those skilled in the art of magnetic circuit and transformer design, and therefore need not be discussed in detail in this specification. Suffice it to point out that, in the present instance the length of the core satisfying this requirement is substantially equal to the longitudinal distance measured along the core axis which is occupied by the various windings associated therewith.

The insulating tube 14 is positioned by a U-shaped mounting bracket 16 having a pair of flanges 18 and 20 to which the ends of the tube 14 are respectively secured by means of removable rivets 22, the flanges 18 and 20 being curved in such a manner that the tube 14 is effectively cradled therein. The entire assembly may be bolted to a television chassis or other apparatus through openings 24 formed in the lower portion of the bracket 16.

A pair of concentric coil windings 26 and 28 are supported by the insulating tube 14, the coil 26 being laid down next to the tube so that it encircles the core member 12, and coil 28 being wound upon coil 26 in the general form of a disc which lies midway between the ends of the latter.

Adjacent to the coil 26 is a further coil 30, these two windings being separated by an insulating spacer 32. The coil 30, as best shown in Figure 3, may consist of not more than two or three turns of wire loosely wound on the tube 14.

While three coil windings have been shown in the drawings, it will be appreciated that the number of such coils employed will depend upon the use to which the transformer 10 is to be put. For example, the coils 26 and 28 may represent portions of an auto-transformer for the horizontal deflection circuit of a television receiver employing a surge-type rectifier, while the coil 30 may represent the rectifier heater winding. However, it should be clearly understood that the number and arrangement of the coils them-

selves forms no specific part of the present invention, and that numerous other winding arrangements may be used if desired in place of the one illustrated.

5 Mounted on one of the side members of the bracket 16 is a terminal board 34 having a central aperture through which projects one end of the insulating tube 14, as well as the flange 20 to which that end of the tube 14 is attached by 10 the rivets 22. This construction is best shown in Figure 4. Additional rivets 36 secure the terminal board 34 to the support 16.

15 Terminal board 34 is provided with a number of connector lugs A, B, C, D and E. When the transformer 10 is utilized as a coupling element in a horizontal deflection circuit of the type shown in Figure 5, then the lugs A and E are respectively joined to the ends of the winding 26. This permits the anode of a power output tube 20 to be connected to the terminal E, and the positive terminal of the B+ supply to be connected to the terminal A either directly or through a so-called "boost" condenser as shown in the drawing. Lugs B, C and D respectively represent 25 taps on the winding 26, as also indicated by the circuit arrangement of Figure 5. Accordingly, the terminal D may be connected to the cathode of a diode damper tube, and terminal B connected to one end of an adjustable width-control inductor the other end of which is joined to terminal A. A pair of high-efficiency deflection coils 30 are connected across the terminals A and C. These may be of the sort described and claimed in my aforementioned copending application. 35 Winding 28, which is the high-voltage, or step-up, winding of the transformer 10, has its high-voltage end connected to a terminal F on the board 34, to which point a cable 36 is also soldered or otherwise securely attached. This cable leads to the anode of the high-voltage rectifier tube shown in Figure 5. It will of course be apparent that whereas a specific number of terminals or lugs have been illustrated as being mounted on the panel 34, nevertheless the number and nature of these terminals will depend upon the design of the particular circuit in which the transformer 10 is to be employed.

45 The performance and efficiency of the transformer 10 depends in part upon the nature of material composing the cylindrical core 12. It may be desirable at times to remove the core so that another one having different operating characteristics may be used. In order to accomplish this without completely disassembling the transformer, there is provided prong 38 which constitutes an extension of one of the side members of the bracket 16. This prong 38 (the insulating tube 14 being partially cut away in Figure 3 in order clearly to bring out this construction) projects through an opening 40 formed in the tube 14 in such a manner that, when the cylindrical core 12 is in position, the prong 38 lies flat against one of the end surfaces of the core.

60 However, when it is desired to remove the core 12 for replacement or other reasons, the rivets 22 are extracted from that end of the transformer. This permits a separation of the tube 14 and the flange 18, the prong 38 withdrawing through the aperture 40. Since the prong is no longer present to hold the core 12 in position, the latter may be easily removed from the tube 14. Following the insertion of another core element, the tube 14 is again brought in contact 65 with the flange 18 and the rivets 22 reinserted.

ough such replacement means is only necessary at one end of the transformer, it may obviously be employed at both ends if found necessary or desirable.

The high-voltage winding 28 is provided with a relatively large number of turns as compared to a standard transformer. Normally this would mean that the retrace portion of each scanning cycle would be increased to a prohibitive degree. In the case of the transformer as described in the present application, this undesirable increase in race time is not present due to the looser coupling between the turns of the winding which results from the relatively small amount of core material employed. Thus it is possible to achieve high-voltage output from the transformer, while at the same time maintaining the inverse voltage on the damper tube and the direct "kick" of the power tube comparatively low. This simplifies circuit design and permits cheaper power tubes to be utilized. If it is found that the relatively loose coupling between turns of the high-voltage winding causes a tendency of the transformer to "ring," this tendency can be almost completely overcome by slightly increasing the efficient of coupling between turns by the use of wire having a slightly higher degree of resistance. For example, if fine magnetic wire is substituted for the usual copper wire, the coefficient of coupling will be increased, while at the same time the circuit losses will not be appreciably greater since the current drawn by the cathode-ray tube does not normally exceed 10^{-4} amperes. At the same time, the use of cheaper iron wire further reduces the cost of the transformer.

Another advantage obtained through the use of a transformer constructed in accordance with the showing of Figures 3 and 4 is that the high-voltage winding 28 has a relatively low capacitance to ground. This is due principally to the absence of a closed core, since, when such a core is used, its proximity to the "high" end of the step-up winding reduces the L/C ratio of the transformer and undesirably increases the proportion of each deflection cycle that is required for retrace. Inasmuch as only a single "slug" is employed in the transformer of the present disclosure, there is no iron mass near the "high" end of the winding 28, and hence the minimum "snap-back" time is determined in practice mainly by the reactance of the remaining components of the deflection circuit.

The absence of a closed core in the transformer has a still further advantage over conventional designs in that the danger of arcing between this element and the H.-V. winding 28 is effectively eliminated. This introduces a factor of safety into the deflection circuit that could not otherwise be obtainable.

Although the assembly of Figures 3 and 4 has been shown to include only a single high-voltage rectifier heater winding 30, it is obvious that the number of such windings depends upon the number of high-voltage rectifier tubes which are utilized.

Further it is to be understood that, while the specific transformer herein described for use in the circuit according to the invention is of the form commonly referred to as an autotransformer, the invention is not limited to the use of such a transformer. On the contrary, if desirable other forms of transformers, such as those having separate primary and secondary windings may be utilized.

Having thus described my invention, I claim:

1. In a combined deflecting and high-voltage supply system for cathode-ray tubes, a source of deflecting energy, a cathode-ray beam deflecting yoke and a circuit for rectifying a portion of said deflecting energy to provide a high potential for supplying the second anode of a cathode-ray tube, the energy required by said high-potential rectifying circuit constituting a relatively large fraction of the total energy supplied by said source to both said yoke and said rectifying circuit, and an open-core transformer having input terminals connected to said source and having output terminals connected respectively to said deflecting yoke and said rectifying circuit and serving as an energy transfer device supplying energy from said source to both said deflecting yoke and said rectifying circuit, the core of said transformer having an air gap sufficiently large to cause a portion of the total energy supplied by said source to be stored in the field surrounding said transformer, said portion being substantially equal to the portion of the total supplied energy which is required by said high-potential rectifying circuit.
2. A combined deflecting and high-voltage supply system according to claim 1 in which said transformer is provided with a common winding to which are connected both the input terminals and also the output terminals associated with the said deflecting yoke, said transformer in addition being provided with a further winding, constituting an extension of said common winding, to which is connected the output terminal associated with the said rectifying circuit.
3. A combined deflecting and high-voltage supply system according to claim 2, wherein the wire of which the said further winding is composed has a higher coefficient of resistance than the wire comprising the said common winding.
4. A combined deflecting and high-voltage supply system according to claim 1 in which said transformer is provided with a plurality of windings arranged to overlie the said core, the configuration of the latter being such that it is substantially completely contained within the space occupied by the said windings.
5. In a combined deflecting and high-voltage supply system for cathode-ray tubes, a source of energy, a cathode-ray beam deflecting yoke having a given impedance and a circuit for rectifying a portion of said energy to provide a high potential for supplying the anode of a cathode-ray tube, the energy required by said high potential rectifying circuit constituting a relatively large fraction of the total energy supplied by said source of both said yoke and said rectifying circuit, and an open core transformer having input terminals connected to said source and having output terminals connected respectively to said deflecting yoke and said rectifying circuit, said transformer serving as an energy transfer device for supplying energy from said source to both said deflecting yoke and said rectifying circuit, said transformer exhibiting at the output terminals thereof connected to said deflecting yoke an impedance value smaller than the impedance value of said deflecting yoke, the core of said transformer having an air gap sufficiently large to cause a portion of the total energy supplied to said transformer by said source to be stored in the magnetic field surrounding said transformer, said portion being substantially equal to the portion of the total supplied energy which

is required by said high-potential rectifying circuit.

6. A combined deflecting and high-voltage supply system according to claim 5 wherein an output terminal of said transformer comprises an intermediary tapping point of a winding element connected to said input terminals, and wherein the said deflecting yoke is connected to said intermediary tapping point.
